HEDDLE FRAME SUPPORT

Richard T. Osteen, Greenville, S. C., assignor to Walker Manufacturing Company, Incorporated, Philadelphia, Pa., a corporation of Pennsylvania

Original application June 17, 1943, Serial No. 491,215, now Patent No. 2,344,212, dated March 14, 1944. Divided and this application November 2, 1943, Serial No. 508,703

6 Claims. (Cl. 139—92)

The object of the invention is to provide improvements in loom harnesses, generally speaking, and more particularly in the means for supporting and elevating the heddle frames and/or returning said frames to their depressed positions, this application being a division of Serial No. 491,215, filed June 17, 1943.

Since early times, the fibrous cord heddles of certain looms have been supported directly by and between transversely extending, vertically spaced shafts, and probably in order to distribute the tension as equally as possible, the cables, straps, etc. employed to elevate the heddles have been attached to intermediate portions of said shafts, that is, at points well within the outer limits thereof. Such looms having fibrous heddles are today used almost exclusively in schools, institutions and by individuals. However, even with the advent of the steel wire (i. e., ribbon-like) heddle in commercial looms and the step by step improvement in supporting the same, usually by and between heddle bars spaced from the shafts within the heddle frame, the method of supporting, elevating and depressing the same has remained substantially the same, although the intermediate attachment of the cables, straps and the like has never ceased to interfere with a weaver's ready access to the opposite sides of the frame from one side only, as when necessary or desirable to lean or reach over it for various reasons.

One of the principal objects, therefore, is to apply the tension of the cords, straps, or the like, to those points or parts of the heddle frames that are stronger and better able to take the strain, thereby removing the strain from the shafts substantially only, as has heretofore been the case. The strongest parts are obviously the metal end pieces or spacing members, and while it is true that intermediate portions of the frame at times have been braced and strengthened, in order to stand the strain of present-day constructions, attaching the straps, cables and the like in alignment with such intermediate braces obviously shifts the straps and cables definitely into the space needed by the operator in attending to his loom.

The present method of supporting heddle frames in looms is by strapping them to hooks and eyes in the shafts at points well removed from the end members, usually about one-quarter of the length of the frame from each end. For example, in a 45-inch frame the straps or other supports are usually about 10 or 11 inches in from the opposite sides. As a result, the strain

and stress is delivered to the shaft, whence the shaft transmits this strain outwardly to the said end members, causing the shaft to bend or flex an indeterminate and varying amount, as no two pieces of wood are exactly alike or bend exactly similarly, while no two are duplicates as to inherent strength.

The result is that too much wear and tear is placed upon the heddles, which are the most expensive part of the frame. In turn, the heddle bars are hard to keep properly adjusted, and when not properly adjusted, that is, parallel throughout the length of the frame, said heddles break, causing both frequent loom stoppages and generally unsatisfactory work. Therefore, in stopping the shafts from bending, by relieving them of the function of directly elevating and lowering the weight of the entire frame, including the many heddles which it carries, and instead expecting nothing from said shafts except to support and maintain the heddles parallel, one is able to offer the mills substantially longer heddle life, and more satisfactory service from both heddles and frames as long as they are in use.

A further and more specific object is to provide a construction of this type, in which the straps, cords and the like of the elevating and depressing harness are attached directly to the shafts, but as closely as may be convenient and feasible to the ends thereof. Proceeding still further, the straps or the like hereinbefore referred to may extend through bores in said shafts and have knots or other means on their ends to prevent them from slipping through and from said bores, said bores extending either wholly or but partially through said shafts.

With the objects thus briefly stated, the invention comprises further details of construction and operation, which are hereinafter fully brought out in the following description, when read in conjunction with the accompanying drawing, in which Fig. 1 is an elevational view of a frame and harness for looms comprising one embodiment of the invention; Fig. 2 is an enlarged fragmentary sectional view of a corner of the frame; and Fig. 3 is an enlarged elevational view of a similar corner portion showing a modified form of attaching means.

In considering this invention, it is to be noted that in old installations only the upper shaft need be changed, whether in the case of new frames in old machines and harness setups, or in remodeling old frames in existing installations, in order to make both sides of the frame equally

accessible from either side, while installed in operative position. On the other hand, it is preferable to alter or initially provide both shafts with the improved construction, so that the frame is thereby invertible as well as reversible.

In the claims, reference to "one of said shafts" is for the purpose of covering cases in which only the upper shaft is altered or made in accordance with the invention, while the lower shaft remains as long in common use, since there is probably no need, even if it should be possible, to reach both sides of the frame from beneath the same. However, the term "one of said shafts" equally covers use of the invention upon either one or both of said shafts.

Also in the claims, the phrase "frame-shifting means" is intended to include use of cables, straps, springs, or weights, and equivalent means which may be employed for elevating a heddle frame from above or depressing it from below, and the invention therefore equally covers the connections between said frame and whatever devices may be used for the purposes mentioned.

Furthermore, the intent of the invention is to cover all manner of connections between cables, straps, springs, weights and the like on the one hand, and the end and closely adjacent portions on the other hand, regardless of whether said connections are by direct contact of the said cables, straps, etc., with the heddle frame (i. e., shafts, spacing bars, or extensions of either), or indirectly through the interposition of hooks, eyes, lugs and their equivalents, as suitable attaching means for said cables, straps, etc.

Referring to the drawing, there is here shown a harness frame for looms, which frame comprises upper and lower shafts 1 and 2, which are spaced apart by means of spacing members 3 at their opposite ends. In one form of such frame, the opposite ends of said members are formed in such manner as to provide terminal portions 4, which are bent angularly inwardly and secured as by means of screws or the like to the opposite outer sides of the respective shafts, while adjacent to the lower end of each of said members depends an eye 5 to which is attached an expansion spring 6, weight, or other suitable means, for normally holding said frame in its lowermost position.

In order to still further secure said side or end members to said shafts, angle members 9 are provided upon the adjacent inner sides of said shafts, and secured thereto and to said members in any suitable manner. Each side member is also provided with pairs of aligned apertures 10, through which extend the end portions of heddle bars 11, carrying heddles 12 of any desired type in the usual manner. Each of said bars is secured in position by means of resiliently positioned hooks or latches 13, carried by the side members and extending through apertures 14 in said bars. The heddle-supporting structure is old and well known, but is here illustrated in order to convey the complete idea of the operative association of a standard form of heddle or harness frame and its several parts, except as herein described, with the elevating and depressing harness herewith illustrated.

In order to show that the invention anticipates the attachment of the harness to said frame in different ways, as long as such attachment is adjacent, and its strains and stresses are applied, to the side members, reference is made more particularly to the details of construction as shown in Fig. 2. At each corner of the frame an angle

member 9 is secured by suitable means to the inner surface of the adjacent shaft, and to said side member in any suitable manner, as by welding at 16. Said angle member is elongated inwardly in a shaft recess 11 and provided with an aperture 12 in alignment with a bore 19, which extends vertically through said shaft, and through which aperture and bore extends one end of a supporting or depressing cable, strap, or the like, 20, the end of which is prevented from escaping by knotting or otherwise fastening it to a washer 21 or the like, which is larger than said aperture and bore. In this construction, the pull of the harness, either or both above and below said frame, while not in direct alignment with said side members, is sufficiently in alignment therewith to fulfill the requirements of the invention, and thereby leave maximum space adjacent to the said shafts free from obstruction, while imposing the necessary elevating and depressing forces almost entirely in alignment with the side members, with no appreciable flexing moment upon the horizontally extending shafts 1 and 2.

25 Referring to Fig. 3, the side and angle members bear the same numerals as in Fig. 2, but instead of the bore 19 which extends through the entire vertical extent of each shaft, a shortened bore 22 is employed, extending inwardly from 30 the outer surface of each of said shafts and receiving the threaded shank 23 of an eye 24, said shank being adjustably secured in position by means of a nut 25 positioned within an enlarged cut-out portion 26 of said shaft.

35 As shown in Figs. 1 and 2, either or both the elevating and depressing means, in extending through bores in said shafts, may reach and project from the inner adjacent surfaces of said members, or may terminate short of said inner 40 surfaces, whether said bores extend entirely or but partially through said shafts.

Having thus described my invention, what I claim and desire to protect by Letters Patent of the United States is:

45 1. A heddle - supporting frame, comprising spaced shafts, spacing members having angular extensions and connecting the end portions of said shafts, heddle bars operatively supported between said shafts, and frame-shifting means, said shifting means being connected to said angular extensions.

50 2. A heddle - supporting frame, comprising spaced shafts, spacing members having angular extensions upon the inner or adjacent sides of said shafts and connecting the end portions of said shafts, heddle bars operatively supported between said shafts, and frame-shifting means extending through bores in said shafts and connected to said angular extensions.

55 3. A heddle - supporting frame, comprising spaced shafts, spacing members connecting the ends of said shafts, brackets carried by said members and engaging the inner or adjacent surfaces of said shafts, and frame-shifting means extending from opposite directions and directly engaging said brackets.

60 4. A heddle - supporting frame, comprising spaced shafts, spacing members connecting the ends of said shafts, brackets carried by said members and engaging the inner or adjacent surfaces of said shafts, and frame-shifting means extending from opposite directions through bores in said shafts and directly engaging said brackets.

65 5. A heddle - supporting frame, comprising spaced shafts, spacing members connecting the

ends of said shafts, pairs of spaced brackets carried by the end portions of each of said members and positioned upon the opposite sides of said shafts, and frame-shifting means extending from opposite directions and directly engaging the inner bracket of each of said pairs.

6. A heddle - supporting frame, comprising spaced shafts, spacing members connecting the ends of said shafts, pairs of spaced brackets car-

ried by the end portions of each of said members and positioned upon the opposite sides of said shafts, the inner bracket being the longer of each pair, and frame-shifting means extending from opposite directions through bores in said shafts and directly engaging the inner bracket of each of said pairs.

RICHARD T. OSSTEEN.
